REVERSIBLE FEED MECHANISM FOR
MACHINE-GUNS

Forrest K. Howard, East Falls Church, Va.

Application January 20, 1933. Serial No. 652,645

8 Claims. (Cl. 89—33)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a reversible feed mechanism for machine guns and is an improvement on the mechanism shown in U. S. Patent No. 1,803,351 of May 5, 1931.

In the patent, a breech bolt is provided with 10 two intersecting cam paths interrupted at the point of intersection to receive a switch block which is adjustable to selectively complete either one of the cam grooves depending on the operation of a right or left handed cartridge feeding 15 mechanism. In the construction shown in the patent the breech bolt has been weakened in the vicinity of the pivot of the switch block with the result that the bolt soon cracks.

The purpose of the present invention is to provide 20 an arrangement whereby the switch block may be mounted without unduly weakening the breech bolt and whereby the block may be firmly supported against rotation.

To these and other ends, the invention consists in the construction, arrangement and combination of elements described hereinafter and pointed out in the claims forming a part of this specification.

30 A practical embodiment of the invention is illustrated in the accompanying drawing, wherein:

Figs. 1 and 2 are plan views of a breech bolt showing the two positions of adjustment of the 35 switch block.

Figs. 3 and 4 are detail views in plan and elevation of the switch block.

Fig. 5 is a view partly in side elevation and partly in section showing the relation of the bolt to the cartridge feeding mechanism.

40 Figs. 6 and 7 are plan views showing the positions of adjustment of a modified switch block.

Referring to Figs. 1 to 5 by character of reference there is shown a portion of a machine gun including a casing 5 having a transverse feedway 6 in which a reversibly mounted slide 7 is reciprocated by means of a lever 8. The lever 8 is pivoted in the casing through the pin 9 and has a stud 10 riding in a cam path in the upper face of a breech bolt 11 that is movable axially of the casing.

There are two oppositely inclined intersecting cam paths on the upper face of the breech bolt, one being employed for moving the slide 7 to advance a cartridge belt from right to left and the other being employed when the belt is to be

advanced from left to right. The two cam paths are formed by grooves 12 and 13 interrupted at their point of intersection by a recess 14 in which is placed a switch block 15 having a single groove 16. The switch block is adjustable to selectively complete either one of the grooves 12 and 13 and likewise to block off the groove not completed.

In order not to weaken the breech block and also in order to provide extended lateral support to the switch block, the recess 14 is defined by 60 parallel side walls 17 and 18 extending longitudinally of the bolt and each positioned an appreciable distance from the side of the breech bolt. The end walls 19—19 of the recess are preferably formed on a curve drawn from the center of the 65 intersection of the cam paths.

The switch block 15 is symmetrical about a longitudinal axis and is substantially of diamond shape having opposite parallel faces *a—a* and *b—b* with rounded ends *c—c*. The groove 16 is formed on the long axis and extends between the rounded ends *c—c*. When the switch block is placed in the recess 14 it is held against rotation by virtue of the engagement of its sides *a* 70 or *b* with the parallel side walls 17 and 18 of the recess. The switch block is additionally held against rotation and also against withdrawal from the recess by means of a locking pin 20 which is insertable transversely in the bolt and 75

engages a stem 21 on the switch block. The locking pin constitutes the pivot of the extractor lever 22 which is provided in the conventional mechanism of the Browning gun for withdrawing a cartridge from the belt and lowering it across 80

the front face of the bolt so that it may be positioned to enter the barrel. The stem 21 is provided with two sets of opposite notches *d—d* and *e—e*, one of which will be presented to the locking pin in the four positions of adjustment of the 85

switch block. These four positions of adjustment are obtained by moving the switch block through an angle less than 45° to selectively complete the cam paths or by moving it through an angle of over 180° to produce the same result.

90 As clearly shown in Fig. 1 the inner side of the extractor lever 22 is in prolongation of the side wall 17 of the recess and is utilized to provide lateral support in one of the positions of adjustment.

A small spring 23 carried by the stem of the switch block and acting on the floor of the recess 14 tends to raise the block and facilitate its removal when the locking pin is withdrawn.

95 In the modification shown in Figs. 6 and 7 the lateral support for the left side of the switch 100

110

block 24 is provided in one instance by means of a lug 25 fitting into a recess 26 in the block, and in the other instance the right side of the block is laterally supported throughout its length 5 by the right wall 27 of the recess.

I claim:

1. In a machine gun, a breech bolt having two intersecting cam paths interrupted at the intersection by a recess having parallel side walls, a 10 symmetrical switch block receivable in the recess, said block being substantially diamond-shaped with a cam path formed on the long axis of the diamond, the opposite sides of the block engaging the opposite sides of the recess when 15 the block is in position of adjustment with its cam path completing either one of the interrupted cam paths, a stem on the switch block having two sets of opposite notches, and a pin insertable transversely of the bolt and engageable 20 with one of the notches.
2. In a machine gun, a breech bolt having two intersecting cam paths interrupted at the intersection by a recess having parallel side walls, a 25 symmetrical switch block receivable in the recess, said block being substantially diamond-shaped with a cam path formed on the long axis of the diamond, the opposite sides of the block engaging the opposite sides of the recess when the block is in position of adjustment with its cam 30 path completing either one of the interrupted cam paths, and means for engaging the block in any position of its adjustment to hold it against rotational displacement.
3. In a machine gun, a breech bolt having two 35 intersecting cam paths interrupted at the intersection by a recess having parallel side walls, a symmetrical switch block receivable in the recess, said block being substantially diamond-shaped with a cam path formed on the long axis of the diamond, the opposite sides of the block engaging the opposite sides of the recess when the block is in position of adjustment with its cam 40 path completing either one of the interrupted cam paths.
4. In a machine gun, a breech bolt having two intersecting cam paths interrupted at the intersection by a recess having parallel side walls, an extractor lever mounted in the bolt and having its inner side in prolongation of one of the side 45 walls of the recess, a switch block having a cam path receivable in the recess, said block having 50

four oppositely parallel sides, a pair of sides being in engagement with the walls of the recess and the extractor when the block is in any position of adjustment with its cam path completing either one of the interrupted cam paths.

80

5. In a machine gun, a breech bolt having two intersecting cam paths interrupted at the intersection by a recess having parallel side walls, a 85 switch block having a cam path receivable in the recess, said block having four oppositely parallel sides, a pair of sides being in engagement with the walls of the recess when the block is in any position of adjustment with its cam path completing either one of the interrupted cam paths.

85

6. In a machine gun, a breech bolt having two intersecting cam paths interrupted at the intersection by a recess having one side wall extending longitudinally of the bolt, a switch block receivable in the recess, said block being substantially diamond-shaped with a cam path formed on the long axis of the diamond, one side of the block engaging the side wall of the recess when the block is in any position of adjustment with its cam path completing either one of the interrupted cam paths, and means for additionally 100 engaging the block in any position of its adjustment to hold it against rotational displacement.

90

7. In a machine gun, a breech bolt having two intersecting cam paths interrupted at the intersection by a recess having one side wall extending longitudinally of the bolt, a switch block receivable in the recess, said block having a cam path, one side of the block engaging the side wall of the recess when the block is in any position of adjustment with its cam path completing either one of the interrupted cam paths, and means for additionally engaging the block in any position of its adjustment to hold it against rotational displacement.

95

8. In a machine gun, a breech bolt having two intersecting cam paths interrupted at the intersection by a recess having one side wall extending longitudinally of the bolt, a switch block receivable in the recess and having a cam path for selectively completing either one of the interrupted paths, said block adjustable to selectively complete the interrupted cam paths by a movement through less than 45° or more than 180°, and the block engaging the side wall of the recess in any position of adjustment.
